UNITED STATES PATENT OFFICE.

EDWARD BENSON, OF MIAMI, ARIZONA.

PUMP.

1,175,503.

Specification of Letters Patent. Patented Mar. 14, 1916.

Application filed October 28, 1914. Serial No. 869,026.

To all whom it may concern:

Be it known that I, EDWARD BENSON, a citizen of the United States, residing at Miami, in the county of Gila and State of Arizona, have invented certain new and useful Improvements in Pumps, of which the following is a specification.

This invention relates to pumps which are double acting, and its object is to provide in 10 a pump of this kind a novel and improved arrangement of valves and hollow plunger rods and also to provide a pump which is highly efficient in operation.

Other objects and advantages of the invention will be made clear in the detailed description appearing hereinafter, and in order that the same may be better understood, reference is had to the accompanying drawings in which—

20 Figure 1 is an elevation of the pump, partly in section; Figs. 2 and 3 are enlarged sections on the lines 2—2 and 3—3, respectively, of Fig. 1, and Figs. 4 and 5 are cross sections on the lines 4—4 and 5—5, respectively, of Fig. 3.

Referring specifically to the drawings, Fig. 1 shows the pump provided with two cylinders 10, but this is immaterial as any number of cylinders may be employed. One 30 of the cylinders is shown in section in Fig. 1, and as the construction of the cylinders and the parts operating therein is the same a description of one suffices for both. The cylinders are mounted in a well 11, their 35 lower ends being submerged in the water to be raised from the well. At the top of the well is an overflow pipe 12.

The pump cylinder 10 is composed of several sections suitably connected by bolting flanges 13. To the lower end of the cylinder is bolted or otherwise connected a valve chamber 14 having a bottom inlet opening over which seats a valve 15 which opens to admit water to the chamber and 45 closes to prevent the water from flowing back into the well. The valve has a depending guide stem 16 working in guides 17 carried by the bottom of the chamber. The upper end of the cylinder is enlarged and 50 flared as indicated at 18. In the lower end of the cylinder 10 works a plunger 19 carried by a hollow rod 20. The plunger has a central opening which communicates with the interior of the rod, and said opening is 55 provided with a valve 21 which is pivoted to swing upward to open position to admit

water from the chamber 14 into the rod. The plunger also has ports which establish communication between the chamber 14 and the space in the cylinder 10 above the plunger. These ports are controlled by valves 23 which open upward.

In operation, when the plunger 19 and the rod 20 are on the upstroke, the water in the cylinder 10 above the plunger is lifted and 60 discharged, the valves 23 being held closed by the weight of the column of water above the same. The valve 15 opens on this stroke to admit water from the well 11 into the chamber 14. The water in the rod is not 65 discharged on the upstroke but is simply carried up with the rod, the valve 21 being held closed by the weight of the water above the same. On the downstroke, the valve 21 is forced open and more water enters 70 the rod, resulting in the discharge of water from the upper end of the rod. At the same time, the valves 23 open to admit water into the cylinder from the chamber 14 through the ports 22. The valve 15 closes 75 on the downstroke.

The rod 20 is operatively connected at the upper end to a crank shaft 24 driven from any suitable source of power. The upper end of the rod is open and the discharge of water takes place therefrom. In 80 the enlarged upper end 18 of the cylinder 10 is a horizontal partition 25 having a central opening through which the rod passes. The partition slopes down from the center, 85 and above the partition, the part 18 of the cylinder has an outlet 26. Below the partition is a second outlet 27 to which the outlet 26 is connected outside the cylinder. The water discharged from the rod 20 flows 90 through the outlet 26, the discharge taking place above the partition 25, whereas the outlet 27 is for the water in the cylinder. The outlet 27 is connected to a pipe 28 which conducts the water to a place of use. 95

The cylinders 10 are supported in the well 11 by means of suspension rods 34 carried by a suitable frame work 35 and connected at their lower ends to rings 36 encircling the cylinders. The frame work is located at the top of the well and has cross-timbers 37 on which rest angle pieces 38 secured to the outside of the cylinders. 105

The rod 20 carries a number of air tight chambers 39 which are submerged in the 110 water in the cylinder 10 when the pump is in action. By means of these chambers the

power required to operate the pump is better distributed between the strokes.

I claim:

1. A pump comprising a cylinder having an inlet chamber at its lower end and a top outlet, an inlet valve for said chamber, a plunger working in the cylinder and having a central opening, a hollow rod connected to the plunger over said opening, a valve controlling the flow from the aforesaid chamber through the plunger opening into the rod, the plunger also having ports opening from the chamber into the cylinder space above the plunger, and valves for said ports.
2. A pump comprising a cylinder having an inlet chamber at its lower end and a top outlet, a partition in the upper end of the cylinder above the outlet, above which partition the cylinder has a second outlet,

an inlet valve for the aforesaid chamber, a plunger working in the cylinder and having a central opening, a hollow rod connected to the plunger over said opening; the upper end of the rod being open and discharging into the cylinder above the partition, a valve controlling the flow from the aforesaid chamber through the plunger opening into the rod, the plunger also having ports opening from the chamber into the cylinder space above the plunger, and valves for said ports.

In testimony whereof I affix my signature in presence of two witnesses.

EDWARD BENSON.
